CALENDAR STAND WITH MEMORANDA
PAPER SUPPLY

Harold G. Davis, Brooklyn, N. Y.

Application August 24, 1945, Serial No. 612,412

5 Claims. (Cl. 312—62)

1

My invention relates broadly to stationery, and more particularly to a desk appliance for dispensing memoranda paper.

One of the objects of my invention is to provide a construction of memoranda paper dispenser for a desk appliance by which memoranda sheets may be readily presented, and conveniently withdrawn for the entry of memoranda.

Another object of my invention is to provide a memoranda paper dispenser which may be readily associated with a desk appliance, such as a calendar, for conveniently presenting memoranda paper sheets for the entry of memoranda from time to time and to which resilient means are connected for directing the memoranda sheets at such an angle that withdrawing of the sheets is facilitated.

Still another object of my invention is to provide an attachment for desk calendar stands for presenting memoranda paper sheets immediately adjacent the calendar for facilitating the entry of memoranda.

Other and further objects of my invention reside in a simplified assembly of paper delivery device for desk calendars, as set forth more fully in the specification hereinafter following by reference to the accompanying drawings in which:

Figure 1 is a side elevational view of a desk calendar stand showing the memoranda paper delivery device of my invention associated therewith; Fig. 2 is a top plan view of the calendar stand and memoranda paper delivery device, as shown in Fig. 1; Fig. 3 is an enlarged longitudinal sectional view taken on line 3—3 of Fig. 2 and illustrates the association of the memoranda paper delivery device of my invention with the calendar; Fig. 4 is a fragmentary transverse sectional view taken substantially on line 4—4 of Fig. 3 and illustrates the arrangement of memoranda paper delivery device of my invention in plan view; Fig. 5 is a vertical sectional view taken substantially on line 5—5 of Fig. 3; Fig. 6 is a vertical sectional view taken substantially on line 6—6 of Fig. 3, and Fig. 7 is a perspective view of the angularly movable paper delivery shelf employed in the structure of my invention.

I have found the structure of my invention as herein set forth very convenient as a desk appliance for storing and presenting a supply of memoranda paper and it is in the form of a tray in the end of a desk calendar stand. Memoranda sheets are continually available through the end of the dispenser, as provided by the structure of my invention for the making of memoranda from time to time. A person at a desk constantly

2

has occasion to require the use of small pieces of paper for notes or for scratch work. The dispenser means of my invention associated with a desk calendar insures a continuous supply of such memoranda paper in a location where it is always serviceable.

Referring to the drawings in more detail, reference character 1 represents a desk calendar stand having inwardly directed longitudinally extending flange portions 1a and 1b, and a supporting top portion 1c. The longitudinally extending inwardly directed flanges 1a and 1b terminate in end portions 1e. The remaining structure of 1 is formed on a diagonal 1f at its open extremity constituting a dispensing end structure as shown. The supporting top portion 1c constitutes a surface for supporting the multiplicity of calendar sheets 2 which are maintained in position by the transversely extending follower plate 3, and the clamping screws 4.

The end of the frame constituted by the calendar support is open throughout the area of the compartment or pocket 5 which is defined by the wall structure constituted by members 6 and 7 formed in plates which extend substantially at an obtuse angle with respect to each other. Within the pocket thus formed in the end of the calendar stand, I arrange an angularly shiftable shelf 9 shown more particularly in Fig. 7. The angularly shiftable shelf 9 is provided with lugs, or tabs 10 and 11 extending in the plane thereof and an angularly disposed rear wall portion 12 extending between the lugs. The rear wall portion 12 is disposed at an acute angle with respect to the plane of the shelf 9. The angularly disposed portion 12 thus serves as a backstop for the memoranda paper sheets which are stacked on the shelf 9 for spreading the stacked sheets substantially in echelon for enabling the sheets to be conveniently taken one at a time through the open end of the calendar stand at 5.

The rear wall 12 is apertured at 14 and 15 in substantial alignment with apertures 16 and 17 in the rear wall 6 of the compartment or pocket 5 for the passage of coil springs 18 and 19. Coil springs 18 and 19 are attached at their ends 18a and 19a through the apertures 14 and 15 of the rear wall 12 of the angularly shiftable shelf 9 and are attached at their ends 18b and 19b to the longitudinally extending flange portions 1a and 1b of the calendar stand 1. The coil springs 18 and 19 tend to continuously urge the angularly movable shelf 9 in an upward direction toward the edge 1d of the calendar stand 1 and away from the ends 1e of the longitudinally extending

flanges 1a and 1b and the opposite edge 8 of the pocket or compartment 5. The tabs or lugs 10 and 11 on shelf 9 extend to the junction of the plate members 6 and 7 designated at 20. Contact between the lugs 10 and 11 and the junction 20 of the plate members 6 and 7 is yieldably maintained by the operation of coil springs 18 and 19, permitting shelf 9 to angularly shift about junction 20 as a fulcrum between the limits of the edge 1d of the calendar stand, and the edge 8 of the compartment or pocket 5. The calendar stand is mounted on rubber feet which I have represented at 22. The rubber feet 22 extend through the calendar stand and are provided with button-like retaining heads 22a. Adjacent the end of the compartment or pocket 5, these retaining button-like heads 22a project upwardly a sufficient distance to serve as resilient limiting stops or bumpers against which the angularly movable delivery shelf 9 strikes when it is depressed during a dispensing operation. This cushioning substantially eliminates any noise which might otherwise result by the striking of the undersurface of angularly shiftable shelf 9 against the upper surface of the plate member 7.

The shelf 9 provides a support for a stack of loose paper sheets 21 which project from the end of the calendar stand, as shown in Figs. 1-4. The acute angle of the backstop 12 with respect to shelf 9 serves to spread the paper sheets 21 in echelon arrangement while the sheets are clamped against the edge 1d of the calendar stand.

In withdrawing the paper memoranda sheets from time to time slight pressure is exerted against the stack of paper sheets 21 on angularly shiftable shelf 9, which tends to rock angularly shiftable shelf 9 about the junction 20 as a center, thereby removing the stack of paper sheets 21 from clamping engagement against edge 1b and allowing withdrawal of a selected memorandum sheet from the top of the stack of memorandum sheets 21. Upon withdrawal of such top sheet the slight pressure against the stack of sheets 21 is removed, allowing shelf 9 to be immediately restored to a position in which the next succeeding sheet on the stack 21 is clamped by the edge 1d of the calendar stand.

After the stack of memoranda sheets 21 is consumed, the stack of memoranda sheets may be readily renewed by introducing a fresh supply of paper sheets from time to time.

I have found the structure of my invention very practical in manufacture and convenient in use, but I realize that modification in structure may be made, and I desire that it be understood that I intend no limitations upon my invention other than may be imposed by the scope of the appended claims.

What I claim as new and desire to secure by Letters Patent of the United States is as follows:

1. A flat sheet dispenser comprising a frame structure open at one end thereof, an open-ended compartment formed in the open end of said frame structure, said compartment including a pair of plate members extending at an angle to each other with a junction therebetween, an angularly shiftable shelf member having a pair of lugs extending therefrom into pivotal engagement with the junction of said plate members and angularly rockable through the open end of said compartment, means on said angularly shiftable shelf member for retaining a stack of flat sheets in superimposed relation, and spring means interconnecting said last mentioned means and said frame structure for urging said angularly

shiftable shelf member to a position successively clamping the stack of flat sheets against a wall of said compartment.

2. A flat sheet dispenser comprising a frame structure open at one end thereof, an open-ended compartment formed in the open end of said frame structure, said compartment including a pair of plate members extending at an angle to each other with a junction therebetween, an angularly shiftable shelf member having a pair of lugs extending therefrom into pivotal engagement with the junction of said plate members and angularly rockable through the open end of said compartment, an end member integrally connected with said angularly shiftable shelf member and extending at an acute angle with respect to the plane thereof for maintaining a stack of flat sheets in echelon arrangement thereon and spring means connected between said end member and said frame structure for urging said shelf member to a position for successively clamping the flat sheets thereon against a wall of said compartment.

3. A flat sheet dispenser comprising a frame structure open at one end thereof, an open-ended compartment formed in the open end of said frame structure, said compartment including a pair of plate members extending at an angle to each other with a junction therebetween, an angularly shiftable shelf member having a pair of lugs extending therefrom into pivotal engagement with the junction of said plate members and angularly rockable through the open end of said compartment, an outstruck end member extending between said pair of lugs and constituting a back support for flat superimposed sheets, and spring means fastened at one end to said frame structure and extending through one of the plate members of said compartment and fastened at the other end to said outstruck end member for continuously urging said angularly shiftable shelf member about said lugs as a center for removably clamping said flat sheets against a wall of said compartment for successive disengagement therefrom.

4. A flat sheet dispenser comprising a frame structure open at one end thereof, an open-ended compartment formed in the open end of said frame structure and extending from the open end of said frame structure to a position beneath said frame structure, a shelf for dispensing paper sheets pivotally mounted in said compartment beneath said frame structure and extending through the open end of said compartment, resilient buffers on the lower portion of said compartment constituting resilient stops for the swinging movement of said shelf, a rear wall on said shelf for supporting flat sheets thereon for delivery through the open end of said compartment and means extending between said rear wall and said frame structure for biasing said shelf to a position in which the flat sheets thereon are successively clamped against the upper portion of said compartment for release upon downward movement of said shelf toward said resilient buffers.

5. A flat sheet dispenser comprising a frame structure open at one end thereof, an open ended compartment formed in the open end of said frame structure and extending from the open end of said frame structure to a position beneath said frame structure, a shelf for dispensing paper sheets pivotally mounted in said compartment beneath said frame structure and having a finger actuating portion extending through the

open end of said compartment, a rear wall on said shelf for supporting flat sheets thereon for delivery through the open end of said compartment and means extending between said rear wall and said frame structure for biasing said shelf to a position in which the flat sheets thereon are successively clamped against the upper portion of said compartment for release upon downward movement of said shelf by application of pressure against said finger actuating portion.

HAROLD G. DAVIS.
